CLAIM

(52) **U.S. Cl.**

The ornamental design for a fiber inspection probe, as shown and described.

USPC **D10/78**

DESCRIPTION

(58) **Field of Classification Search**

FIG. 1 is a top, front left perspective view of a fiber inspection probe showing my new design.

USPC D10/75, 78

FIG. 2 is a bottom, rear right perspective view thereof.

CPC .. G01M 11/088; G01M 11/00; G01M 11/005;

FIG. 3 is a front elevational view thereof.

G01M 11/08; G02B 6/385; G02B 6/3898;

FIG. 4 is a top plan view thereof.

G02B 6/25; G02B 6/3807; G02B 6/3866;

FIG. 5 is a left side elevational view thereof.

G02B 6/3885; G02B 6/3846; G02B

FIG. 6 is a rear elevational view thereof.

6/3863; G01B 11/2441; G01B 11/303;

FIG. 7 is a right side elevational view thereof; and,

G01N 21/8806; G01N 21/952

FIG. 8 is a bottom plan view thereof.

See application file for complete search history.

The broken lines are for the purpose of illustrating portions of the fiber inspection probe that form no part of the claimed design.
